UNITED STATES PATENT OFFICE.

JOHN WILEY EDMANDS, OF NEWTON HIGHLANDS, MASSACHUSETTS, ASSIGNOR TO
CENTRAL RAILWAY SIGNAL COMPANY, OF BOSTON, MASSACHUSETTS, A CORPO-
RATION OF NEW JERSEY.

RAILWAY SIGNAL TORPEDO.

Application filed October 22, 1923. Serial No. 670,054.

To all whom it may concern:

Be it known that I, JOHN W. EDMANDS, citizen of the United States, residing at Newton Highlands, in the county of Middlesex and State of Massachusetts, have invented certain new and useful Improvements in Railway Signal Torpedoes, of which the following is a specification, reference being had therein to the accompanying drawing.

10 This invention relates to improvements in railway signal torpedoes and its primary object is to provide means for closing the ends of the tubular container in such a manner as to prevent the explosion from causing any flying parts liable to cause personal injury.

15 A further object of the invention is to provide the torpedo with a clip located beneath it and adapted to receive and clamp the extended ends of the tubular case whereby all parts liable to fly when the torpedo is exploded are held to the rail thus avoiding personal injury.

Another object of the present invention is 25 to provide a clip located against the bottom of a tubular case, the clip receiving and clamping the elongated ends of the case, and the clip provided with means for receiving and holding a rail-fastening strap.

30 Further objects of the invention will appear from the following description and disclosures.

In the accompanying drawings:

Figure 1 is a top plan view of my improved railway signal torpedo.

Figure 2 is a sectional view on the line 2-2 of Figure 1.

Figure 3 is a top plan view of the tube out of which the case is formed.

40 Figure 4 is a cross section view of the tube.

Figure 5 is a plan view showing the ends of the case doubled to enter the holding clip.

45 Figure 6 is a plan view of the holding clip.

Figure 7 is a plan view of the holding clip with the rail engaging strap held thereto.

50 Figure 8 is an end view showing the method of attaching the torpedo to the clip and the strap in position on the clip.

In constructing my improved torpedo the case 1 is formed from a section of a tube, the tube being composed of suitable fibrous material. Located under the tube is a clip

3 which is preferably composed of metal though it may be composed of hard fiber or other suitable material. This clip is provided near each end with transverse slits 4 and at its center with a projection 5 which is stamped from the center of the clip. Preferably, though not necessarily, the clip is provided at opposite sides of its center with inwardly extending cutaway portions 6 which provide for movement of the strap 7. The type of strap 7 here shown is the ordinary lead strap, and it is provided with a central opening 8 through which the projection 5 passes, the said projection being bent downward as shown in Figures 7 and 8. Preferably this clip is bent upwardly as shown at about the points 9, for a purpose to be described hereinafter.

While I have described the use of a lead strap I desire it understood that an ordinary spring strap could be added to the clip without departing from the spirit of the invention.

The form of explosive we show is a molded tablet 10 but loose powder may be used if desired.

In constructing the torpedo the explosive 10 is placed within the tube, and is considerably shorter than the tube 1. After the explosive is in position the ends which extend beyond the explosive are doubled inward as shown at 11 which provides center point portions 12. One of these extended portions 11 is inserted through one of the slots 4 the strap 7 placed in position as shown in Figure 8 and then the other portion is inserted through the opposite slot. After the torpedo case is applied to the clip, the clip may be mashed down upon the ends 11 though that will not be necessary in order to make a hermetically sealed case. The folded end portions 11 may be held in position by the use of an ordinary form of water-proof cement, and the whole torpedo after being constructed coated with a water-proof compound.

It will be observed that with this form of torpedo the clip portion and the strap, are the only parts capable of flying and causing personal injury. In this construction these parts are located wholly below the case so that the force of the explosion will not tear them nor make any flying parts, which would be the case if any part of the clip were located above the case. The con-

struction provides an absolutely safe non-flying torpedo construction and is a construction that is usually sought by the railroads.

5. The whole torpedo is a simple and cheap one to produce as well as being extremely efficient and safe in use. In this construction the ends of the clip are entirely enclosed by the extended ends 11 of the case.

10. I desire it understood that variations in the construction may be made and the object carried out without departing from the spirit and scope of the appended claims.

Having thus described my invention what 15. I claim and desire to secure by Letters Patent is:

1. An improved torpedo comprising a case having extended ends, a clip below the case having openings passing through it, the 20 extended ends of the case passing through the said openings, and a pair of the extended ends resting between the case and the said clip.

2. An improved torpedo comprising a 25 tubular case, a clip applied to the bottom of the case, the clip having openings, and the case having extended ends passing through the said openings.

3. An improved torpedo comprising a 30 case having extended ends, a clip below the case, the extended ends of the case doubled around the clip, and the said clip con-

structed to permit a part of the extended ends to lie between the bottom of the case and the said clip.

35. 4. An improved torpedo comprising a tubular case having extended ends, a clip applied to the bottom of the case, the clip having an intermediate projection, a rail-engaging strap held in position by the projection, the clip applied to the bottom of the case and its extended ends folded inward around the ends of the clip and means for holding the folded ends in position.

40. 5. An improved torpedo comprising a tubular case having extended ends, a clip applied to the bottom of the torpedo, said clip having a depressed center portion and slots located in the depressed portion, and the extended ends of the case doubled inward and passing through the said slots.

45. 6. An improved torpedo case having extended ends, of a clip located below the said case and having a depressed central portion, the extended ends of the case bent around the ends of the clip, the clip provided with passages located above the depressed portion to receive a part of the extended ends of the case, whereby a part of the extended ends of the case lie between the 50 clip and the bottom of the case.

55. In testimony whereof he hereunto affixes his signature.

JOHN WILEY EDMANDS.
